UNITED STATES PATENT OFFICE.

JOHN A. CROSS, OF WESTWOOD, NEW JERSEY.

SPRING DOOR-CLOSER.

1,094,306.

Specification of Letters Patent. Patented Apr. 21, 1914.

Application filed December 6, 1913. Serial No. 805,097.

To all whom it may concern:

Be it known that I, JOHN A. CROSS, a citizen of the United States, residing at Westwood, in the county of Bergen and 5 State of New Jersey, have invented new and useful Improvements in Spring Door-Closers, of which the following is a specification.

This invention relates to door closers, the 10 primary object being to provide a closer which may be applied to any swinging door conveniently and without making any extensive alterations in the door frame or the door itself and which, when applied, 15 will not prove an obstruction or unsightly object.

A further object is the provision of a device of this character which will serve to close the door with which it is used in a 20 positive manner, but which will not cause the door to slam suddenly so as to jar the same and make unnecessary noise.

A still further object is to provide a door closer whose spring may be regulated conveniently in effective tension, and which may be adjusted for use upon a door which opens in one direction, or for use upon an oppositely opening door, as desired.

Figure 1 is a fragmentary front elevation 30 of a door frame and door mounted therein, showing the preferred embodiment of my invention applied thereto, the door being closed; Fig. 2 is a fragmentary plan view of the same showing the door partially 35 open; Fig. 3 is a vertical sectional view taken through a portion of the door and the guide plate mounted thereon, showing the actuating arm of the closer connected operatively therewith, the latter being broken away; 40 Fig. 4 is a vertical sectional view taken through a portion of the door frame, showing the body of the closer mounted therein, in side elevation; Fig. 5 is a longitudinal sectional view through the closer; Fig. 6 is 45 a transverse sectional view on line 6—6 of Fig. 5; and, Fig. 7 is a detail sectional view taken longitudinally through the saddle member.

In the drawings, I have shown the frame 50 1 of a door in connection with which the device is to be used as provided adjacent to the hinged edge of the door 2 with a vertical opening 3 in its lintel. The base plate 4 of the door closer is counter-sunk within the 55 lower face of the lintel spanning the said

opening as at 3^a, and is secured in this position by means of the attaching screws 5. This plate is provided centrally with an opening 6 in which the lower end of a vertical shaft 7 is rotatably mounted.

A horizontally movable actuating arm 8 is provided in one of its ends with a non-circular opening 9 receiving the reduced non-circular portion 10 of the said shaft, which extends downwardly from the bearing flange 11 of the shaft and protrudes below the plate 4. The bearing flange 11 frictionally engages the upper face of the plate 4 and thus supports the shaft. The actuating arm is secured to the shaft by 65 means of a binding screw 12 and the washer plate 13. The shaft 7 is provided with a pair of right hand spiral grooves 14 which intersect a pair of left hand spiral grooves 15, which are of extremely high pitch. A 70 hollow, cylindrical saddle member 16 is mounted upon the shaft for rotary and longitudinal sliding movement thereon, and it is provided interiorly with a pair of threads 17 which, in this instance, are left hand 75 threads and are adapted for engagement within the grooves 15 of the shaft. The saddle member 16 has its upper end portion enlarged as at 18 to provide a shoulder 80 19 which is adapted to engage an annular bearing plate 20 which embraces the lower portion of the saddle member. This bearing plate is provided in its outer periphery with a plurality of circumferentially spaced 85 slots 21 for the reception of the longitudinally extending guide rods 22 between which the said bearing plate is slidably mounted. The plate 20 is provided interiorly with an arcuate slot 23 which is 90 adapted to receive the lug 24 which projects 95 inwardly from a locking sleeve 25, the latter being positioned upon the reduced portion of the saddle member with its inner edge abutting the bearing plate. The locking sleeve is secured detachably in its operative 100 position upon the saddle member by means of a set screw 26. A strong helical spring 27 is positioned upon the shaft 7 between the lower end of the saddle member and the bearing flange 11. This spring is adapted 105 to be placed under compression when the arm 8 is operated so as to rotate the shaft 7 in such a direction that the saddle member will be forced downward. It should be apparent that, when the arm 8 is subsequently 110

released, the spring 27 will expand and thus cause upward movement of the saddle member and consequent rotation of the shaft in reverse direction.

- 5 The free end of the actuating arm 8 is provided with a vertical opening 28 in which the upper end of a friction pin 29 is threaded. This pin is engageable within the longitudinal slot 30 provided in an elongated guide 10 plate 31, which latter is secured detachably upon the upper edge of the door adjacent to its hinged edge. The friction pin 29 is slidably engaged within the said slot and the head 32 provided upon its lower end is 15 constructed greater in diameter than the width of the slot so as normally to prevent disengagement of the pin from the guide member, but the remote end of the slot is provided with a widened portion 33 through 20 which the head of the pin may be removed conveniently without the necessity of detaching the plate 31 from the door. A longitudinal groove 24 is formed in the upper edge of the door coextensive with the slot 25 30 in the guide plate, through which the head of the friction pin is freely movable. In this instance, the door 2 is mounted to swing so that, upon being opened, the actuating arm 8 will be moved in clockwise 30 direction (looking downwardly), thereby causing like rotation of the shaft 7, whereupon the saddle member will move downward and will thus place the spring 27 under tension. When the door is released, 35 the spring will expand and force the saddle member upward. The resulting rotation of the shaft in counter-clockwise direction will cause the actuating arm to swing inwardly toward the door frame and thus close the door in a positive and steady manner, due to the sliding engagement of its friction pin 29 within the slot of the door-carrier bearing plate 31.

In order to obviate slamming of the door 45 which would otherwise result, a reacting buffer spring 35 is mounted upon the upper end of the shaft 7 between the saddle member 16 and a limiting collar or head 36 which is secured terminally upon the shaft by means of a set screw 37. The buffer spring 50 may be regulated in effective tension by adjustment of the collar 36 upon the shaft. When the device is used in connection with a heavy door, the collar 36 should be forced 55 downward to place the spring 35 under considerable tension before the set screw 37 is tightened. The door closer may be adjusted for use in connection with an oppositely movable door by replacing the saddle member 60 used in the foregoing connection by a saddle member having right hand threads therein for engagement with the right hand grooves of the shaft. The device may also be adapted for use in connection with a 65 door which opens in both directions by re-

placing the comparatively weak buffer spring with a heavy spring equal in resistance to the main spring 7.

From the foregoing description, taken in connection with the accompanying drawings, it should be apparent that I have provided a simply constructed and efficient spring closing device which may be used upon various kinds of doors. It is to be understood, however, that minor changes in the details of construction, such as fall within the scope of the appended claims, may be resorted to in practice whenever desired.

What is claimed is:

1. In a device of the class described, the combination with a door frame and a door hinged thereto, of a supporting plate mounted in the frame, a shaft journaled in the said plate and being disposed parallel to the axis of the door pivot, the said shaft being provided with a spiral groove, a saddle member rotatably and slidably receiving the said shaft, a spiral thread provided within said saddle member for operative engagement within the shaft groove, means for preventing rotation of the saddle member with respect to the supporting plate during its longitudinal sliding movement upon the shaft, a flange provided upon the shaft, a compression spring mounted between the saddle member and the shaft flange, and means connecting the said shaft with the door to cause cooperative movement thereof.

2. In a device of the class described, the combination with a door frame and a door hinged thereto, of a supporting plate mounted in the frame, a shaft journaled in the said plate and being disposed parallel to the axis of the door pivot, the said shaft being provided with a spiral groove, a saddle member rotatably and slidably receiving the said shaft, a spiral thread provided within said saddle member for operative engagement within the shaft groove, a guide rod connected with the said supporting plate and disposed parallel to the shaft, a bearing plate mounted fixedly upon the saddle member and having a slot therein frictionally engaged with the guide rod, a flange provided upon the shaft, a compression spring mounted between the saddle member and the shaft flange, and means connecting the said shaft with the door to cause cooperative movement thereof.

3. In a device of the class described, the combination with a door frame and a door hinged thereto, of a supporting plate mounted in the frame, a shaft journaled in the said plate and being disposed parallel to the axis of the door pivot, the said shaft being provided with a spiral groove, a saddle member rotatably and slidably receiving the said shaft, a spiral thread provided within said saddle member for operative engagement within the shaft groove, means for prevent-

ing rotation of the saddle member with respect to the supporting plate during its longitudinal sliding movement upon the shaft, resilient means for resisting longitudinal movement of the saddle member in one direction, further resilient means for resisting the movement of the saddle member in the opposite direction, and means connecting the said shaft with the door to cause 10 coöperative movement thereof.

4. In a device of the class described, the combination with a door frame and a door hinged thereto, of a supporting plate mounted in the frame, a shaft journaled in the said plate and being disposed parallel to the axis of the door pivot, the said shaft being provided with a spiral groove, a saddle member rotatably and slidably receiving the said shaft, a spiral thread provided 20 within said saddle member for operative engagement within the shaft groove, means for preventing rotation of the saddle member with respect to the supporting plate during its longitudinal sliding movement upon 25 the shaft, resilient means for resisting longitudinal movement of the saddle member in one direction, a helical spring for resisting movement of the saddle member in the opposite direction, the said spring being positioned surrounding the shaft with one end abutting the said member, an adjustable sleeve mounted upon the said shaft in engagement with the opposite end of the 30 spring, means by which the said sleeve may be secured in adjusted position upon the shaft, and means connecting the shaft with the door to cause coöperative movement 35 thereof.

5. In a device of the class described, the combination with a door frame and a door hinged thereto, of a supporting plate mounted in the frame, a shaft journaled in the said plate and being disposed parallel to the axis of the door pivot, the said shaft being provided with a spiral groove, a saddle member rotatably and slidably receiving the said shaft, a spiral thread provided 40 within said saddle member for operative engagement within the shaft groove, a guide rod connected with the said supporting plate and disposed parallel to the shaft, the said saddle member being provided with an annular enlargement at one end thereof forming a shoulder, an annular bearing plate mounted upon the said saddle member in 45 engagement with its shoulder and having a slot in its inner periphery, a locking sleeve positioned upon the reduced portion of the saddle member in engagement with the bearing plate, a lug formed upon the inner end of the said sleeve for engagement within the said plate slot, means for securing the said sleeve fixedly in its applied position upon the shaft, the said bearing plate having a slot in its outer periphery frictionally 50 engaged with the guide rod, yieldable means for resisting movement of the saddle member in one direction, and means connecting the said shaft with the door to cause coöperative movement 55 thereof.

In testimony whereof I affix my signature in presence of two witnesses.
